UNITED STATES PATENT OFFICE

2,253,317

DRAWER FOR REFRIGERATED LOCKER SYSTEMS

William McKinley Baird, Chicago, Ill.

Original application January 26, 1939, Serial No. 252,973. Divided and this application April 12, 1939, Serial No. 267,472.

2 Claims.

(Cl. 45—7)

This is a divisional application of the original application Serial No. 252,973 filed in the United States Patent Office on January 26, 1939, for Refrigerated locker system, now Patent 2,198,239.

Among the objects of my invention is to provide drawers for a refrigerated locker system in which side and rear angles are used for the direct support of the mesh portion, the bottom pan and the front insulated door. My drawers for refrigerated locker system have such other objects, advantages and capabilities as will later more fully appear and which are inherently possessed by my invention.

While I have shown in the accompanying drawing a preferred form of my invention yet I wish it understood that the same is susceptible of modification and change without departing from the spirit of my invention.

Referring to the drawing:

Fig. 1 is a detailed face view of my drawer; Fig. 2 is a side elevation partly broken away to show the bottom pan; Fig. 3 is a rear elevational view; Fig. 4 is a detailed sectional view on line 4—4 of Fig. 2, and Fig. 5 is a top plan view of my drawer.

The embodiment selected to illustrate my invention discloses drawers for use in a refrigerated locker system. Each of the drawers 26 has a pair of side angles 27 connected by tie or rear angles 28. At the rear of said side angles 27 each of said drawers 26 has a roller 29 adapted to facilitate the movement of the drawer on the tracks of the frame of the refrigerated locker system. Attached to the front ends of the side angles 27 is a front face door 30 which has attached to its inner surface suitable insulation 31. Wire mesh is attached to the rear angles 28 to form a rear screen 32, and wire mesh is also attached to the side angles 27 to form side screens 33. A bottom pan 34 is held in place preferably by the same bolts that fasten the rear angles to the side angles. The front edge of the bottom pan may be turned up with the edge turned back and with holes in the turned up portion to receive bolts for attachment

to the front of the door. Each door has a suitable handle 35 containing retaining and locking mechanism.

The front face 30 of the drawer 26 extends forwardly so as to be substantially flush with the outer face of the shell of the refrigerated locker system when in closed position. Each drawer 26 has a gasket 36 attached to the inner edges of a flange 37 on the face 30 so as to seal the drawer upon the same being in closed position.

Having thus described my invention, I claim:

1. A drawer for a refrigerated locker system comprising two pairs of spaced side angle members, with one pair of said side angle members located at each side of the drawer, rear angle members connecting said side angle members, a front face door attached on its inner surface to the front ends of said side angles, wire mesh attached to said side angle members to form side screens, wire mesh attached to said rear angle members to form a rear screen, a solid bottom pan attached to said side angle members, said bottom pan having a front turned-up edge attached to said front door, and a handle attached to said front door.

2. A drawer for a refrigerated locker system comprising a frame composed of two pairs of side angles with one pair of said side angles at each side of the drawer, and rear angles connecting said side angles, screens attached to said side and rear angles respectively to enclose the drawer, a solid metal pan attached to said rear and side angles to form a bottom closure for said drawer, a front face door attached to the front ends of said side angles, said front door having insulation attached to its inner portion, said pan having a front turned-up and back portion with holes therein, a plurality of bolts extending through said holes and into the inner portion of said front face door for attachment of the pan thereto, and a handle attached to the outer surface of said front door.

WILLIAM MCKINLEY BAIRD.
